SOLVENT REFINING OF FATTY OILS

Herbert J. Passino, Englewood, N. J., assignor to
The M. W. Kellogg Company, Jersey City, N. J.,
a corporation of Delaware

Application January 13, 1948, Serial No. 1,942

8 Claims. (Cl. 260—428.5)

1

This invention relates to improvements in a method of separating mixtures of high molecular substances, such as animal fats and oils, vegetable oils and waxes and similar mixtures of non-hydrocarbon organic substances or mixtures of high molecular hydrocarbons with high molecular non-hydrocarbon substances into fractions having different compositions. More particularly, the invention relates to improvements in methods of fractionating such oils into extract and raffinate phases with a solvent whose miscibility with the oil decreases with increasing temperature. Still more particularly, the invention relates to a method of refining the raffinate phase by recycling a portion of said phase to the fractionating zone, with or without the addition of solvent.

A principal application of the improved process is the treatment of fatty oils to separate a relatively small proportion of the oil as the desired product. An example of this type of operation is the treatment of natural oils to separate therefrom fractions which are concentrated in vitamins. A second application of the invention is in the treatment of oils whose constituents all have molecular weights of the same order of magnitude in order to separate the oil into fractions in accordance with differences in chemical constituents; it is desirable to accomplish this separation without chemical treatment. An example of this application of the invention is the treatment of palm oil to obtain a concentrate of the pro-vitamin A carotenoid, as described in Patent No. 2,432,021, entitled "Concentration of Vitamin A Carotenoids" and assigned to The M. W. Kellogg Company. As described in that case a carotenoid concentrate may be obtained in the raffinate phase of a continuous counter-current fractionation of palm oil with a normally gaseous hydrocarbon solvent, preferably propane. The method disclosed herein provides a means for further refining the carotenoid concentrate.

In other cases, the invention provides a means for salvaging an extract material carried down into the raffinate phase. For example, in the decolorization and refining of tallow by solvent fractionation with propane in a continuous counter-current tower system, the crude tallow may contain as little as one per cent of color bodies or other undesirable impurities. Conventional fractionation makes it possible to obtain a very high grade, decolorized tallow from the extract by fractionating the crude tallow into a 97 per cent extract fraction and a raffinate

fraction; this, however, represents a loss of three per cent tallow in the raffinate. It is possible, of course, to subject the raffinate to a second propane fractionation but this is expensive and requires an additional tower and a second counter-current stream of propane. According to the present method a raffinate fraction of three per cent or more is withdrawn but the greater portion of it is reintroduced into the fractionating tower at a point above the lower phase level and above the point at which the solvent is introduced. The recycled raffinate is thus all or partly dissolved and is subjected to rectification by being again precipitated in the lower portion of the tower. In one preferred form, a small amount of propane is added to the recycled portion of the raffinate in order to facilitate its flow and its conversion, at least in part, to upper phase solution. It is to be noted, however, that the quantity of propane which must be added at this point is much less than would be needed for a second fractionating tower so that it is a much more economical means of scavenging all possible extract matter from the raffinate.

Furthermore, the effects of the addition of propane to the recycled raffinate can be used to achieve the same results as if a much larger quantity of propane were introduced directly into the fractionating tower. In many cases it is desirable but costly to have a very high ratio of solvent to oil treated. For example, if the tower is operated with a charge of 10 volumes of solvent for each volume of oil, and the addition of 5 volumes of solvent for each volume of raffinate recycled, the results in the case of some oil will be substantially the same as if the solvent to oil charge ratio were much greater than 10; actually, the total propane employed will be only slightly greater than 10 times the volume of charge oil because the amount of raffinate recycled per hour is small relative to the charge oil so that the amount of propane necessary to dilute the recycled raffinate 5 times is relatively small.

In another application of the presently disclosed method of more effectively and more completely fractionating extract material from raffinate material, a concentrated lecithin product is obtained from the raffinate fraction of soybean oil by recycling a portion of the raffinate to the extract phase in order to achieve a "cleaning" action. The color bodies which are present in the soybean oil come down with a lecithin in

the bottoms but these may be readily separated by a subsequent fractionation.

Although the invention is not limited to any particular type of apparatus it may be better understood from the description of a simple form of a solvent extraction tower shown diagrammatically in the drawing. A vertical fractionation tower 10 is shown with the usual propane inlet 11 and valve 11a near the lower or raffinate end 12 and an oil charging line 13, through which the raw charge oil is introduced into tower 10, preferably at some point in the middle third of the tower. Pressure and temperature conditions controlled to cause all or a portion of charge oil introduced through line 13 to go into solution into the solvent introduced through line 11. This solution is then subjected to treatment, such as a gradient of upwardly increasing temperature within the tower provided by any convenient means such as heating coils 14 so as to cause an upper or extract phase 15 and a lower or raffinate phase 16 to be formed therein, separated at some point by an interface 17. Conduit withdrawal means 18 and 19 for continuously or intermittently withdrawing the extract and raffinate phases are provided at the upper and lower ends respectively. Preferably, the extract conduit 18 is introduced into a separating means 20 at a substantially lower pressure in order to flash off part of the solvent through line 21 and to withdraw the extract in concentrated form through line 22. A portion of the extract is recycled to tower 10 through line 23 by means of pump 23a for refluxing purposes, the balance being passed through a pressure reducing valve 24 to a separator 25 at atmospheric pressure, which effects a final separation into extract product to be withdrawn through line 26 and the balance of the solvent which is withdrawn through line 27, recompressed by means of compressor 28 and, joined with the solvent removed in separator 20, is cooled by a cooling means 29 for storage, in liquid form, in storage tank 30. A pump 31 is employed for pumping liquid solvent from storage tank 30 through line 32 and solvent feed line 11 to fractionating tower 10. For example, if a typical solvent such as propane is employed the tower 10 may operate under a pressure of nearly 600 lbs. per sq. inch, separator 20 and storage tank 30 at a pressure of about 200 lbs. per sq. inch, and separator 25 at substantially atmospheric pressure; pump 31 serves as an economical means of obtaining an elevated pressure at tower 10.

The raffinate withdrawn through discharge conduit 19 at the bottom of tower 10 is divided into portions which are determined by the setting of valves 32 and 33 into a recycled portion, usually more than 50 per cent, which is reintroduced into tower 10 by means of line 34 at any point that may be selected by the manipulation of valves 35, 36, or 37, or into charge oil feed line through valves 38. It is necessary for the effective application of my method that the recycled raffinate be introduced into tower 10 at a point not lower than the interface level 17, which is usually but not necessarily at a lower level than the point of entry of the propane line 11. A pump 39 may conveniently be employed for recycling the raffinate. Recycling may be facilitated by means of a small amount of propane introduced through line 40 by opening valve 40a. In the case of most oils, it will be found possible to greatly economize in the use of propane by very substantially reducing the propane introduced into ex-

traction tower 10 through line 11 by partially closing valve 11a while at the same time opening valve 40a only slightly. In many cases the effect is the same as if the solvent to oil ratio within tower 10 were greatly multiplied although the actual amount of propane employed remains the same. The reason is that only a small amount of propane is required to be passed through line 40 to thoroughly dilute the raffinate recycled through line 34. On the other hand, the invention is not limited to the recycling of raffinate with the introduction of propane through line 40a but includes the recycling of raffinate when not diluted and, indeed, even in cases in which it is desolvated. For example, fractionation conditions within the tower 10 may be radically altered by recycling raffinate material which has been cooled or neutralized with alkali before re-introduction into tower 10.

The bottom product, or at least a portion of it, may be conveniently stripped of propane in an intermediate pressure evaporator 41, the separated solvent being delivered through line 42 to intermediate pressure line 21. The product oil is then withdrawn from intermediate pressure evaporator 41 through line 43 to a final separation at atmospheric pressure in an atmospheric pressure evaporator 47 from which raffinate product is withdrawn through line 44 and solvent is withdrawn through line 45 to be recompressed by compressor 46 and returned to intermediate pressure line 42.

Although the invention is not limited to any particular solvent fractionation system and may be used in connection with solvents such as methanol, isopropyl alcohol, phenol, furfural, and the like, it is uniquely adapted for use in fractionation systems employing solvents of low critical temperature, in which the extract and raffinate phases are formed in a range between the temperature of greatest miscibility and the critical temperature, for instance, normally gaseous hydrocarbons, particularly propane, when employed in temperature ranges between critical temperature of 100° F. below critical.

The invention is particularly applicable in the solvent fractionation of a high molecular weight mixture by means of a solvent whose critical temperature is not higher than 450° F. wherein the solvent is introduced at a low point in a vertical solvent fractionation zone and the high molecular weight mixture is introduced at a point substantially above the solvent charging point, and wherein the solvent fractionation treatment is carried out at temperatures between the critical temperature of the mixture and 100° F. below the critical, and in which miscibility of the high molecular weight mixture and the solvent decreases with rising temperature.

Furthermore, the invention is adapted either to concentrating a pure product in the raffinate phase or to achieving a higher recovery in the extract phase.

The invention will be illustrated by reference to an example which relates to the fractionation of soybean oil to obtain phosphatides therefrom by means of solvent extraction with propane in accordance with the method disclosed herein. A commercial soybean oil was subjected to treatment with propane solvent in a combination extraction and rectification tower having an inside diameter of three inches and a height of 60 feet. The oil was charged to the tower at the point about 36 feet from the top at a rate of approximately 4,000 cubic centimeters per hour. A pro-

pane solvent was charged to the tower about 58 feet from the top at a rate of between 40,000 and 120,000 ccs. per hour, i. e. at a solvent to oil volumetric ratio in the range from 10:1 to 30:1. The tower was maintained at between 400 and 500 pounds per square inch pressure. After equilibrium conditions were established in the tower, the oil charged was fractionated to an overhead extract of 98 per cent and a bottoms raffinate of 2 per cent; thus the bottom yield was about 80 ccs. per hour. In the absence of any recycling of the raffinate to the tower, it was necessary to withdraw a bottoms of at least three per cent in order to separate all of the phosphatides therein. When, however, the raffinate was recycled (without the addition of any solvent) it was found possible to concentrate the phosphatides in the bottom two per cent. Thus, the bottoms obtained by operation without recycling is about 60 per cent phosphatides at the maximum; with recycling, the bottoms were about 85 per cent phosphatides, so that less tallow is lost and a better bottoms product is recovered. The amount recycled was varied from 10 ccs. per hour to 200 ccs. per hour, i. e. recycled to yield ratios ranging from 1/2:10. In the case of the particular sample of soybean oil used in this test, an intermediate recycled to yield ratio of approximately 5:1 seemed best. It was also found possible to operate at a much lower solvent to oil ratio and yet achieve superior results.

I claim:

1. In the solvent fractionation of a high molecular weight mixture containing a fatty oil by means of a solvent whose critical temperature is not higher than 450° F. wherein the solvent is introduced at a low point in a vertical solvent fractionation zone and the high molecular weight mixture is introduced at a point substantially above the solvent charging point, and wherein the solvent fractionation treatment is carried out at temperatures in the range between the critical temperature of the mixture and 100° F. below the critical, and in which miscibility of the high molecular weight mixture and the solvent decreases with rising temperature, the improvement comprising withdrawing raffinate solution from a point below the point of introduction of the high molecular weight mixture, and reintroducing a portion of said withdrawn raffinate into said solvent fractionation zone at a point above the point of introduction of said solvent, and not higher than the point of introduction of said high molecular weight mixture.

2. A method as described in claim 1 in which additional solvent is introduced into said recycled portion.

3. An improved method of concentrating lecithin which includes the steps of: continuously introducing a lecithin-containing oil into a vertically extended fractionation zone at a point substantially removed from the lower end thereof; continuously introducing into said fractionation

zone near the lower end thereof a solvent for said oil having a substantially lower density and boiling point than said oil, and a critical temperature not higher than 450° F.; contacting said oil and said solvent in a temperature range between the critical temperature of the mixture and 100° F. below the critical under pressure sufficient to maintain the mixture in a liquid condition; continuously withdrawing an extract phase substantially free of lecithin from the upper portion of said fractionation zone; continuously withdrawing a raffinate phase concentrate in lecithin from a point near the lower end of said fractionation zone; and recycling a substantial portion of said raffinate to said fractionation zone at a point substantially above the point of introduction of said solvent and not higher than the point of introduction of said oil.

4. A method as described in claim 1 in which said recycled portion comprises more than 50 per cent of the withdrawn raffinate.

5. A method as described in claim 1 in which said recycled portion is subjected to cooling before being recycled.

6. A method as described in claim 1 in which said recycled portion is subjected to neutralization with alkali.

7. In the solvent treatment of a fatty oil to remove a relatively small fraction of said oil in a raffinate wherein a solvent having a density and boiling point substantially lower than said oil and a critical temperature not higher than 450° F. is contacted with said oil in a vertically extended fractionation zone in a temperature range between the critical temperature of the solvent-oil mixture and 100° F. below the critical, and in which miscibility of the oil and the solvent decreases with the rising temperature, the improvement comprising: withdrawing raffinate solution from a point below the point of introduction of said oil at a rate substantially in excess of the desired bottom fraction; and reintroducing said excess into said fractionation zone at a point substantially above the point of introduction of said solvent, and not higher than the point of introduction of said high molecular weight mixture.

8. A method as described in claim 1 in which soybean oil is treated to concentrate phosphatides in a bottoms fraction of less than 10 per cent.
